UNITED STATES PATENT OFFICE

136,869

DESIGN FOR A TOY

Pedro Generoso Garcia, Macon, Ga.

Application May 24, 1943, Serial No. 110,266

Term of patent 7 years

To all whom it may concern:

Be it known that I, Pedro Generoso Garcia, a citizen of Cuba, residing at Macon, in the county of Bibb and State of Georgia, have invented a new, original, and ornamental Design for a Toy, of which the following is a specification, reference being had to the accompanying drawing, forming part thereof.

I claim:

The ornamental design for a toy, as shown.

PEDRO GENEROSO GARCIA.
